Primary Examiner — Melody N Brown(74) *Attorney, Agent, or Firm* — Quarles & Brady LLP(57) **CLAIM**

The ornamental design for a material handling vehicle bumper, as shown and described.

DESCRIPTION

FIG. 1 is a top, front and left side perspective view of a material handling vehicle bumper showing our new design; FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The portions of the bumper shown in broken lines are shown for illustrative purposes and form no part of the claimed design.
